UNITED STATES PATENT OFFICE

167,399

BAKERY TYPE TRUCK BODY

Wade O. Ford, San Angelo, Tex.

Application July 31, 1950, Serial No. 11,493

Term of patent 14 years

(Cl. D14—3)

To all whom it may concern:

Be it known, that I, Wade O. Ford, a citizen of the United States of America, residing at San Angelo in the county of Tom Green and State of Texas, have invented a new, original, and ornamental Design for Bakery Type Truck Body, of which the following is a specification; reference being had to the accompanying drawing, forming part thereof.

In the drawings:

Fig. 1 is a perspective view of the right-hand side of the bakery type truck body, showing my new design.

Fig. 2 is a perspective view showing the left-hand side of the body; and

Fig. 3 is a top plan view.

The dotted line showing in the drawing figures is for illustrative purposes only.

I claim:

The ornamental design for a bakery type truck body, as shown and described.

WADE O. FORD.
